UNITED STATES PATENT OFFICE.

CHARLES L. KELLY, OF DETROIT, MICHIGAN.

WRENCH.

1,351,519.

Specification of Letters Patent. Patented Aug. 31, 1920.

Application filed December 24, 1919. Serial No. 347,132.

To all whom it may concern:

Be it known that I, CHARLES L. KELLY, a citizen of the United States of America, residing at Detroit, in the county of Wayne 5 and State of Michigan, have invented certain new and useful Improvements in Wrenches; and I do hereby declare the following to be a full, clear, and exact description of the invention, such as will enable 10 others skilled in the art to which it appertains to make and use the same.

This invention relates to a wrench. It is a primary object and purpose of the present invention to make a wrench which is particularly quick acting for fitting the same to a nut or bolt to be operated upon by the wrench and also one which may be disengaged from the nut or bolt as quickly 15 as it may be engaged therewith. The invention consists of many novel arrangements of parts for attaining this end in an especially effective manner as will appear from the following descriptions, taken in connection with the accompanying drawing, in which:

25 Figure 1 is a plan view of a preferred form of construction of the wrench.

Fig. 2 is a side elevation thereof, one of the side plates being removed to disclose the inner structure, and

30 Fig. 3 is a side elevation of the modified form of construction of the wrench, a part of one of the side plates being broken away.

In the drawing like reference characters refer to like parts in the different figures.

35 In the preferred form of construction shown in Figs. 1 and 2, a central bar 1 is used which is made from steel, preferably, the same at its forward upper edge being inclined downwardly and provided with a 40 series of teeth 2. In front of and below this portion the bar is extended and curved as indicated at 3, terminating in a fixed jaw 4, the inner face of which lies at an angle to the length of the bar. At each side of the 45 bar, plates 5 of metal are placed, being permanently connected to the bar by means of transverse pins 6, a number of which are used.

Associated with this bar is a second jaw 50 member having a jaw portion 7, the inner face of which is parallel to the inner face of the jaw 4 and from which a downwardly and rearwardly extended part 8 projects, said jaw member on its under surface, be-

ing formed with a series of teeth 9 which 55 match and are adapted to co-act with the teeth 2 on the bar 1 previously described. The lower portion 8 of this jaw member lies between the plates 5 and is freely movable toward or away from jaw 4. On its outer 60 side above the plates 5 the movable jaw member has a knurled or otherwise roughened surface 10 to be engaged by the thumb of the operator for moving the movable jaw member toward the fixed jaw 4. The 65 plates 5 are provided with parallel slots 11 and a pin 12 passes through the movable jaw member and has its ends received in the slots, it being apparent that the movement of the movable jaw member is limited 70 by said slots.

A pin 13 is attached to the movable jaw member on the outer side thereof. To it one end of a U-shaped wire 14 is connected, the same extending back from the movable 75 jaw and having its ends formed into coils 15 which are received in suitable recesses cut into the bar 1. The ends of the coils are attached to a transverse post 16 which is held between the side plates 5; these coils 80 have a tendency to pull the movable jaw member to the rear; and whenever said jaw member is moved toward the fixed jaw 4 the coils are tightened and their tension increased as is evident.

To move the movable jaw member toward the fixed jaw member it is necessary merely to take the wrench in the hand and place the thumb against the roughened surface at 10 and push forward on the same whereupon the teeth 9 will ride over teeth 2, and as soon as the jaw member is released the force of the spring will tend to pull the teeth 9 into engagement with teeth 2 thus holding the movable jaw member in any 90 position to which it may be moved. In the drawing the size of the teeth 2 and 9 is necessarily exaggerated for the proper showing thereof, but in practice the teeth are all very shallow in depth and those of the movable jaw member may ride freely over those on the bar 1. The adjustment to the size of any nut or bolt head within the range of the wrench is almost instantly made. To release the wrench it is necessary merely to 95 press with the thumb against the outer end of the movable jaw member at a point above the roughened surface 10 whereupon said

member fulcrums on the pin 12 and elevates the teeth 9 above the teeth 2 so that the spring coils at 15 may draw the movable jaw member back as far as is necessary or desirable.

5 In Fig. 3, a slightly modified form of structure is shown in which the bar 1 is replaced by two parts, one the bar 17 which has a rear spring extension 18, and the other 10 the curved section 3^a formed with a fixed jaw portion 4^a and located at the front end of bar 17. The side plates 5 are used as before and pins 6^a pass through the bar 17 and the part 3^a to secure the parts firmly 15 together. A leaf spring 19 is held at one end between the forward end of bar 17 and the adjacent end of the part 3^a as shown in Fig. 3; and the free end of this spring is curved upwardly and against the inner face 20 of the jaw member 7 which is identical in construction with and is mounted the same as the movable jaw member first described, it having teeth 9 on its under sides to engage with teeth 2 formed on the bar 17.

25 At the rear end of the wrench a screw driver blade 20 and a knife blade 21 may be mounted on a pivot 22 and the same closed to lie between the sides 5 or opened out with the usual jack knife principle of 30 operation, the spring back for which is afforded by the extension 18 to the bar 17. This construction, so far as the wrench is concerned, operates exactly the same as the one first described, the only difference being that a leaf spring 19 resists the inward movement of the movable jaw member instead of a coil spring as shown in Fig. 2.

35 This wrench is of very simple construction and is very quickly and easily operated. It is particularly useful around motor vehicles where nuts of relatively small sizes are used and in which different sizes of nuts require adjustment of the jaws of the wrench to engage therewith.

40 I claim:

45 1. A wrench comprising a bar having a downwardly inclined upper edge portion provided with ratchet teeth, a fixed jaw member at the front end of the bar, side 50 plates permanently secured one at each side of the bar and fixed jaw member; a movable jaw member provided with ratchet teeth on its lower side, said ratchet teeth being adapted to engage with the ratchet teeth on 55 said bar, means for slidably mounting the movable jaw member between the side plates for guidance thereby, and spring means tending to move the movable jaw member away from the fixed jaw member and also hold the teeth of the movable jaw member 60 in engagement with the teeth on the bar, substantially as and for purposes described.

65 2. A wrench comprising an integral bar and jaw member, said jaw member having an inner face located at an angle to the

length of the bar, and said bar having a downwardly inclined upper surface back of the jaw member formed with a consecutive series of ratchet teeth cut transversely of the bar, a movable jaw member mounted 70 above the bar and provided with a consecutive series of ratchet teeth on its under side cut transversely of the movable jaw member and adapted to engage with the ratchet teeth on the bar, means for slidably mounting the movable jaw member whereby the same may move toward or away from the fixed jaw member, and spring means normally tending to move the movable jaw member away from the fixed jaw member 75 and also hold the teeth of the movable jaw member in engagement with the teeth on the bar, substantially as and for the purposes described.

3. In a wrench, spaced apart side plates, 80 a fixed jaw member permanently connected to and lying between the side plates and having a jaw extending outwardly at an angle to the length of the side plates, said side plates being provided with elongated 85 slots back of the fixed jaw member, a movable jaw member located between the side plates, a pin carried by the movable jaw member having ends received in said slots, means for holding the movable jaw member 90 against movement away from the fixed jaw member in any position to which it may be moved with respect to the fixed jaw member and a single yielding means tending to move the movable jaw member away from 95 the fixed jaw member when the holding means is released and also yieldingly maintaining said holding means against release, 100 substantially as described.

4. In a wrench, a bar, a jaw member positioned at an angle to the length of the bar and located at one end of the bar, a movable jaw member located above the bar and movable toward or away from the fixed 110 jaw member, interengaging means on the movable jaw member and the bar for holding the movable jaw member in any one of a number of positions against movement away from the fixed jaw member, and spring means associated with the movable 115 jaw member tending to move the same away from the fixed jaw member, and also yieldingly maintain said interengaging means in engagement, substantially as described.

5. In a wrench, a bar, side plates, one at 120 each side of the bar and permanently connected thereto, a fixed jaw member at one end of the bar, a plurality of ratchet teeth formed on the upper edge of the bar back of the fixed jaw member, a movable jaw 125 member located between the plates, said plates each having a slot therein, means on the movable jaw member entering the slots for slidably mounting the jaw member, said movable jaw member being formed with 130

ratchet teeth on its lower side to engage with ratchet teeth on the bar and holding the movable jaw member in any position to which it may be adjusted against movement 5 away from the fixed jaw member, and spring means associated with the movable jaw member for moving the same away from the

fixed jaw member when the ratchet teeth on the same are disengaged from the ratchet teeth on the bar and also normally holding 10 said ratchet teeth in engagement.

In testimony whereof I affix my signature.

CHARLES L. KELLY.
